Richard N. Allen, 2809 Cherokee Ave.,
Columbus, Ga. 31906

Filed Apr. 27, 1970, Ser. No. 22,679

Term of patent 14 years

Int. Cl. D8—08

U.S. Cl. D8—246

FIG. 1 is a side elevational view of a clothes hanger support for an automobile embodying my new design;
FIG. 2 is a front elevational view thereof; and
FIG. 3 is a bottom plan view thereof.

The broken line representation of an automobile coat hook in FIG. 1 is for purposes of illustration only.

I claim:

The ornamental design for a clothes hanger support for an automobile, as shown and described.
